UNITED STATES PATENT OFFICE.

THOMAS FEYEN, OF DUBUQUE, IOWA.

DOUBLE-TREE PROTECTOR.

SPECIFICATION forming part of Letters Patent No. 317,105, dated May 5, 1885.

Application filed April 30, 1884. (Model.)

To all whom it may concern:

Be it known that I, THOMAS FEYEN, of the city and county of Dubuque, and State of Iowa, have invented a new and useful Improvement 5 in Double-Tree Protectors; and I hereby declare that the following is a full and exact description of the same, reference being had to the accompanying drawings and the letters of reference marked thereon.

10 My invention has for its object to provide a practical, economical, and efficient mode of fastening the single-trees to the double-tree by means of an ordinary clevis-pin without boring through or in any manner weakening the 15 double-tree; and, further, my invention furnishes convenient eye-holes to which the stay-chains of the wagon may be attached.

For the better understanding of my invention, I call attention to the accompanying 20 drawings, in which—

Figure 1 represents one end of a double-tree with my protector and an ordinary clevis, C, and pin B' attached. Fig. 2 represents my protector detached. Fig. 3 represents a side 25 view of my protector, showing ring to which the stay-chains of the vehicle are attached.

Like letters denote corresponding parts in all of said figures.

B represents my protector, (which may be 30 made of wrought or malleable iron,) consisting of the main body with arms a' a', for the purpose of attaching it to the double-tree. There is also cast upon it a projection, E, which enters the evener or double-tree for the purpose 35 of taking the strain off of the screws in case of side pull. Through the center of the protector is a hole, through which a clevis-pin passes to pivot the clevis to the double-tree, and at the back of the protector I cast a ring, 40 to which the stay-chains are attached, instead of attaching them in the ordinary way.

A represents one end of an ordinary double-tree. Upon the side of the double-tree, near the end opposite to which the single-trees are attached, I fasten said protector B by the lug 45 E and screws a a. I then attach to this an ordinary clevis, C, with pin B' through the hole F in the protector B. To the ring D of the protector I attach the ordinary stay-chains, connecting with the axle of the vehicle. 50

By the use of my protector it will be readily seen that the double-tree is not weakened by boring holes through it in order to fasten the clevis and the single-trees to the double-tree, and all the strength of the double-tree is preserved. It will also be observed that the ring 55 D furnishes a convenient, safe, and durable eye-hole to which the stay-chains of the double-tree can be attached, and also thereby doing away with the necessity of boring holes 60 through the double-tree for the purpose of putting in an eyebolt for the stay-chain.

Having thus described my invention, what I claim as new, and desire to secure by Letters Patent, is—

1. A double-tree protector having the lug 65 E, arms a' a', and hole F, for attaching clevis-pin, all placed upon a double-tree and operated substantially as described, and for the purposes shown.

2. In a double-tree protector, the combination of the plate B, having lug E, arms a' a', clevis-pin hole F, and eye-hole D, to which stay-chains are attached, substantially as described, and for the purposes set forth. 75

In testimony whereof I have hereto affixed my signature in presence of two witnesses.

THOMAS FEYEN.
